UNITED STATES PATENT OFFICE.

CHARLES W. HUNTINGTON, OF BALTIMORE, MARYLAND.

ELECTRIC SWITCH.

SPECIFICATION forming part of Letters Patent No. 435,424, dated September 2, 1890.

Application filed January 24, 1890. Serial No. 337,968. (No model.)

To all whom it may concern:

Be it known that I, CHARLES W. HUNTINGTON, a citizen of the United States, residing in Baltimore, in the State of Maryland, have 5 invented certain new and useful Improvements in Electric Switches, of which the following is a specification.

This invention has reference to electric switches and cut-outs.

10 The object is to provide a switch which shall be cheap of manufacture, efficient in operation, and not liable to become deranged from use.

In general the invention consists of a base 15 of insulating material, in the face of which a circular groove or channel is formed, the bottom of the channel being formed of four inclined planes, the opposite ends of each of which are respectively in two parallel planes. Two of 20 these metallic surfaces are armed with metallic plates and the other two are left bare. A centrally-pivoted circuit-controlling arm is provided with contact-brushes at its opposite ends, which, when the arm is turned in one 25 direction, drag over the inclined surface and make or break the electric circuit. A spring is suitably arranged in connection with the circuit-controlling arms to hold the brushes in contact with the inclined surface.

30 Referring to the accompanying drawings, Figure 1 represents a perspective view of the switch with the cover removed. Fig. 2 represents a plan of the same, and Fig. 3 a central section through the base.

35 A represents the base. This may be of wood, porcelain, fiber, or any similar insulating material. Its upper surface is flat, and is provided with a circular groove B, concentric with the base. This groove may or may 40 not be provided with raised edges b for the purpose of deepening the groove and preventing foreign matters from falling into it. On the bottom of this groove is formed four inclined planes or teeth b', which make a 45 form of ratchet on the bottom of the groove. Two of these teeth, which stand opposite each other, are faced with metal and form the switch terminals of an electric circuit. The other two teeth are left bare or are made of 50 any suitable insulating material.

In the center of the base-piece a post C is pivoted. Its lower end is provided with a nut or cross-head c, which plays in and out of a

chamber a in the base. Between the cross-head and the inner extremity of the chamber 55 a spiral spring is placed, the tendency of which is to force the cross-head and the center post outward. Above the face of the block the post has fitted to it a circuit-controlling arm C', which is adapted to turn 60 with the post through a plane substantially parallel to the face of the base of the switch. The extremities of this arm are at diametrically-opposite points just above the groove B, and the said extremities have attached to 65 them trailing contact-pieces c', of spring metal, which extend down into the groove and bear with a yielding pressure upon the bottom thereof. The central base is fitted with a key D of insulating material, by means 70 of which the arm may be thrown around to operate the switch. The object of the groove is to retain the contact-brushes c' squarely upon the bottom or contact plates of the switch, so as to secure good electric connection. Furthermore, if there should be any 75 sparking between the contacts, the same would be confined between the walls of the groove and would not do injury to other parts 80 of the switch.

In operation the key is turned in a single direction, movement in the opposite direction being prevented by the vertical walls between the teeth or inclines. The spring in the chamber a tends continually to hold the 85 brushes to their work, thus insuring good contact.

Having thus described my invention, I claim—

In an electric switch, a base of insulating 90 material having a circular groove formed in its face, the bottom of which is in the form of a series of inclined planes, every alternate plane being metallic and the other planes of insulating material, in combination with a 95 circuit-controlling element working in the groove adapted to make and break contact with the metallic surface mentioned.

In witness whereof I have hereunto signed my name in the presence of two subscribing 100 witnesses.

CHAS. W. HUNTINGTON.
